[57] ABSTRACT

A transporting apparatus in which a series of platforms are driven in a closed-loop, the loop including two similar main segments in adjacent horizontal planes, the upper main segment comprising at least a low speed zone, a curved speed-change zone and a high speed zone and the lower main segment comprising a platform return zone. The apparatus may further include a second curved speed-change zone and second low speed zone. Drive means in the low speed zones are by rotary screws in the high speed zones by powered wheels engaging the platforms and in the speed-change zones by linear motors. The apparatus may be used as a loading or unloading station for a high speed conveyor belt.

TRANSPORTING APPARATUS

The present invention relates to transporting apparatus, such as is used for conveying passengers or goods between points of the type in which the loads being conveyed are loaded onto a low-speed conveyor and subsequently travel on a high-speed conveyor.

An apparatus of this type is disclosed in British Patent No. 1,034,969 in which is described a platform conveyor in which the means for driving the platforms over the various points of the circuit consist firstly of an endless train of screws hingedly connected to one another in succession and disposed along the path followed by the centre of gravity of each platform over the circuit, and secondly of a finger secured underneath each platform and projecting into the thread of the train of screws, such screw serving to bring this train into positive engagement with each platform. In the acceleration and deceleration zones of the circuit described in this patent, the corresponding portion of the screw train has a pitch which respectively increases from the entry end to the exit of the acceleration zone or decreases in the case of a deceleration zone, this screw train portion being rotatably driven by a motor coupled to one end of the portion in question.

This apparatus is however subject to relatively major drawbacks that are inherent to its structure of a purely mechanical nature, some of these drawbacks tending to render the use of this particular form of apparatus awkward or even dangerous, particularly if it is intended for the public transport of people.

In this connection, the safety of the people being conveyed on the platforms is dependent to a very large extent on the continuity of the moving band formed by the platforms, particularly in the acceleration and deceleration zones of the circuit. Such continuity is directly dependent firstly on the machining accuracy of the drive screws and of the platform elements with which these screws are meant to come into engagement, and secondly on the accuracy with which all of these parts are assembled. Under these conditions, it will be appreciated that the production and installation costs of an apparatus of the kind described in the patent can be relatively high. The same applies also to the maintenance costs.

Furthermore, since this is a solution which is wholly mechanical, clearly the various members involved in driving the platforms, in whatever part of the circuit, will be subject to a degree of wear which will become more and more pronounced in the course of use of the apparatus in question, such wear being liable to give rise to sufficiently large mechanical play to cause the platforms to move apart in unexpected manner, or even partial jamming, which can lead to decelerations that are particularly dangerous for passengers, in particular for children, elderly people and the infirm. Such drawbacks can also make themselves felt in the transport of goods, in particular goods of a relatively fragile nature. Further the existence of mechanical play in the described installation can be the source of noise and of platform vibration of an intolerable level for users and, in general, for people and even equipment in the surroundings.

It should further be pointed out that, with the cited apparatus, a break in one of the screws leads to an immediate stoppage in the driving action for a relatively large number of platforms and hence to a deceleration

of all of the platforms of the circuit, and such a deceleration could even be very abrupt if the load being transported by the platforms that are effected by a drive failure is particularly great or if these platforms are those that are momentarily moving over the acceleration or deceleration zone, respectively, of the circuit, where the resistive forces acting on the platforms are among the largest. The particularly serious consequences that can be caused to the goods or people being transported and the importance of the material damage that such jerks could cause will readily be appreciated, whether it be in the upstream part or in the downstream part of the circuit in relation to the platforms that are momentarily blocked.

15 A final drawback of the apparatus described in U.K. Patent No. 1,034,969 lies in the relatively large amount of space occupied by this apparatus, in particular as regards the part thereof which serves to recycle the platforms that successively leave the unloading section and move towards the loading section, this being the circuit portion over which the platforms travel whilst being recycled, and which is practically co-planar with the loading, acceleration, deceleration and unloading portion of the circuit.

20 25 It is one object of the present invention to obviate some of the above drawbacks.

According to one aspect of the present invention a transporting apparatus comprises a series of transport platforms intended to travel over a closed circuit having a low speed zone, a high-speed zone, an intermediate speed-change zone between the low and high-speed zones, the speed change zone being in the form of a curve and the cosine of the angle between tangents at the two ends of the curve corresponding to the ratio of the platform speeds in the low-speed and high-speed zones, and a platform-return run curved at least in part as the speed change zone, wherein the circuit comprises a stretched-out loop comprising firstly, two main segments which are contained, one in a first horizontal plane and the other in a second, subjacent, horizontal plane, and secondly two secondary segments which connect the ends of the said main segments to form the closed circuit, the segment in the upper main segment of the loop comprising at least the said low, high and speed-change zones of the apparatus and the segment in the lower main segment of the loop comprising at least the curved part of the platform-return run.

According to another aspect of the invention the upper main segment of the loop comprises an additional low-speed zone and an additional speed-change zone between the high-speed zone and the additional low-speed zone, the said additional speed change zone being in the form of a curve and the cosine of the angle between tangents at the ends of the curve corresponding to the ratio of the platform speeds in the high-speed and additional low-speed zone, and the lower main segment of the loop comprising the return run of the conveyor comprises low-speed end zones one at each end of the segment, a high-speed central zone and two curved speed change zones, one between each zone and the high-speed zone, each being curved as the speed change zones in the upper main segment.

65 The transporting apparatus is preferably provided with means on each platform enabling detachable, edge-to-edge, hooking engagement with the adjacent platforms, and control means are provided for controlling said hooking means, adapted to engage said hook-

ing means for as long as the platforms move along the main segments of the circuit loop and to release the platforms from hooking engagement when travelling over one or other of said secondary segments of said loop.

Preferably also the platforms may be driven over the closed loop by means comprising in the speed change zone, a succession of linear motors whose stators are disposed to one side at least of the plane of motion of the platforms, along the path followed by the centres of gravity of these platforms, and whose armatures are formed by at least one metallic mass associated with each platform, in the terminal portions of each main segment of the loop a pair of rotary screws extending on opposite sides of the path followed by the centres of gravity of the platforms, in a plane parallel to the plane of motion of the platforms and over a set length from the end of this main segment, the thread of each screw receiving a projecting element on each platform when the platform reaches the entry end of the screw, and axially pushing the projecting element and the platform towards its exit end, a driving device being provided for the screws, and over the other portions of the said main segments of the loop, a driving mechanism engaging with the platforms in at least a portion of each end of the segments.

The driving mechanism may comprise a set of rubber tyred wheels some of which are powered at least some of which are provided with braking means.

Synchronising means may be provided between the various pairs of screws and the driving mechanism as required.

Another aspect of the invention provides a conveyor system comprising a transporting apparatus and an endless belt moving at a constant speed substantially equal to the platform speed in the high speed zone of the loop wherein the speed-change zone accelerates a load from the low speed to the high speed for transfer from the high speed zone to the endless belt, the path of the high speed belt being curved so as to avoid the additional speed-change zone and the additional low speed zone which decelerates a load transferring from the high speed belt to the high speed zone.

Yet another aspect of the invention provides a conveyor system in which the transporting apparatus provides a two-part high-speed zone one running adjacent to one side of the belt for transfer of loads onto the belt and the following part of the high speed running adjacent to the other side of the belt for transfer of loads from the belt for subsequent deceleration the two parts being connected by a high speed zone running under the belt.

Barrier devices may be provided to move loads onto or off the belt as required.

Further aspects of the invention will be apparent from the following description of one embodiment of the invention, by example only, in conjunction with the diagrammatic drawings in which:

FIG. 1 is a developed view in side elevation;

FIGS. 2 and 3 are views along II-II and III-III respectively of FIG. 1;

FIG. 4 illustrates, on an enlarged scale, a partial cross-section along IV-IV of FIG. 2;

FIGS. 5 and 6 are cross-sections along V-V and VI-VI of FIG. 4;

FIGS. 7 and 8 illustrate in elevation and plan the structural features of another detail of FIG. 1;

FIG. 9 is a cross-sectional view along IX-IX of FIG. 1;

FIG. 10 is a view in the direction X-X of FIG. 9;

FIG. 11 is a cross-sectional view along XI-XI of FIG. 1;

FIG. 12 is a view in the direction XII-XII of FIG. 11;

FIG. 13 shows two adjacent platforms in the high speed load carrying position;

FIG. 14 is a view on XIV-XIV of FIG. 13;

FIG. 15 is a view on XV-XV of FIG. 14;

FIG. 16 is a view on XVI-XVI of FIG. 14;

FIG. 17 shows two adjacent platforms in the high speed return zone of the conveyor;

FIG. 18 is a view on XVII-XVII of FIG. 17;

FIG. 19 is a view on XIX-XIX of FIG. 18;

FIG. 20 is a view on XX-XX of FIG. 18;

FIG. 21 shows a conveyor belt to transporter arrangement;

FIG. 22 shows an alternative arrangement to FIG. 21.

The transporting apparatus illustrated in FIGS. 1, 2 and 3 is more particularly intended for the loading of goods or people on to a transporting band 1, of which only a segment is visible in the drawing, and for unloading these goods or people off this band. This band segment moves in a horizontal plane, it is rectilinear over part of its length and is slightly curved at its right-hand end, in the drawing, so as to move sufficiently far away from the exit of the transporting apparatus.

This transporting apparatus consists of a series of platforms 2a, 2b, 2c . . . , 2m, . . . , 2n, etc., moving in joined position over a circuit defined by two guide rails 3 and 4. These rails each form a stretched out loop having two main segments, 3a and 3b, and 4a and 4b, respectively, and two secondary segments, 3c and 3d, and 4c and 4d, respectively. The main segments 3a and 4a are contained in a common horizontal plane, the same applies to the segments 3b and 4b, the plane containing these segments being however situated underneath the plane of segments 3a and 4a. The segments 3c and 4c, and 3d and 4d, respectively, are each of semi-circular shape and are respectively contained in first and second vertical planes that are parallel to each other.

As will be observed from FIG. 2, each of the segments 3c and 4c of the guide rails 3 and 4 comprises five parts A, B . . . E, of which three, A, C and E, are rectilinear whereas the other two B and D, form a curve, i.e. a segment of a parabola.

Similarly, the lower segments 3b and 4b of rails 3 and 4 also comprise five parts A', B', . . . , E', of which those bearing the references A', C' and E' are rectilinear whereas parts B' and D' have a curved outline.

As is known, in particular from the already mentioned U.K. Patent No. 1,034,969 the rectilinear parts of the circuit over which travel the platforms of the illustrated transporting apparatus are those over which these platforms move at constant speed whereas the curved parts, e.g. part E or part B, are those over which these platforms are gradually accelerated or are decelerated. In the present case, the platforms 2a, 2b, 2c etc. are accelerated when they are being driven over parts B and D' of the circuit of the apparatus and are decelerated when they move over parts D and B' of this circuit. It should still be pointed out that the parts C and C' of the circuit are those over which the platforms move at the greatest constant speed, parts A, E, 3d-4d,

E' , A' , $3c-4c$, being those over which the platforms move at the lowest constant speed.

Since the illustrated transporting apparatus is intended to accelerate goods or people for loading on to the transporting band 1, or to decelerate them, once unloaded from the band, the segments $3a$ and $4a$ of rails 3 and 4 are contained in the same plane as that of motion of the band and are parallel to the axis of the rectilinear part thereof. Moreover, the speed at which the platforms move over the circuit part C is identical to the speed V of the transporting band 1. Over the circuit part A, as also over the part A' , and over that formed by the segments $3c$ and $4c$, the speed of motion of the platforms has a value equal to V_o , less than V . The same applies over the circuit parts E and E' as well as over the intermediate part thereof constituted by the secondary loop segments $3d$ and $4d$ formed by the two rails 3 and 4. This speed V_o is chosen to be sufficiently low to enable easy access of the users or of the goods on to part A of the circuit, or to enable unloading of these users or goods from part E of this circuit.

In the example illustrated in the drawing, the ratio of speeds V/V_o is equal to 3.5:1; it can of course be less than this value or in other cases greater than e.g. 5.1. Since moreover, it is desired that the acceleration or the deceleration of the loads being transported by the platforms be uniform, the path imposed by the rails 3 and 4 in both part B and part D of the circuit is parabolic and the axes of entry into part B and of exit from part D, respectively, which are parallel to the rails 3 and 4 in parts A and E thereof, respectively, form with the axis of motion of the band an angle ϕ_o such that $\cos \phi_o = V_o/V = 1/3.5 = 0.286$.

The particular choice of acceleration or deceleration law for the loads is essentially governed by considerations of safety and comfort. The shape of the path followed by the platforms during acceleration or deceleration is of course dependent on this law. These imperatives clearly do not apply as regards the acceleration and deceleration of the platforms moving over the lower part of the loop formed by the rails 3 and 4 since the platforms then travel empty, thus explaining the particularly abrupt deviation that is imposed on the platforms over part B' and over part D' of the circuit.

Viewed from the angle of accelerating up to a speed V the loads coming on to the apparatus at a speed V_o , less than V , or from the angle of decelerating these loads from the speed V to the speed V_o , the circuit of the apparatus illustrated in the drawing comprises in fact the following four sections:

Load acceleration

A first, low speed V_o , section formed by the circuit part A; a second, high speed V , section formed by the left-hand portion of part C; a third section for accelerating the platforms from V_o to V formed by part B; a fourth, platform recycling, section formed by the remainder of the circuit.

Load acceleration

A first, high speed V , section formed by the straight portion of part C; a second, unloading, low speed V_o , section formed by part E; a third, platform deceleration, section formed by part D; a fourth, load recycling, section formed by the remainder of the circuit.

This consideration leads us to point out that it would clearly be possible, in a constructional variant not shown in FIGS. 1 to 3 to cut the transporting apparatus forming the subject of FIGS. 1 to 3 into two separate

parts of which one would essentially serve to accelerate loads and the other to decelerate loads, which parts could of course be sited at locations far removed from each other; (some arrangements will be described below).

As will in particular be observed from FIG. 2, each of the platforms $2a$, $2b$, $2c$, ..., $2m$ etc. has in plan, the shape of a trapezium of which one of the small sides, here that indicated by the reference a in the case of platform $2a$ (FIG. 2), forms with one of the two parallel sides, here the side b , an acute angle α such that $\alpha = \phi_o - \pi/2$ if π_o is the angle lying between the two vectors V and V_o and defined by the already mentioned relationship; $\cos \phi_o = V_o/V$.

Each platform is formed by a segment from a shaped structural member, of substantially rectangular cross-section, which is partly hollowed out internally and which is for instance produced by extrusion (FIG. 4).

On its top surface, each element is lined with a plate 5 from which project a series of parallel ribs 5a for providing the users or the goods loaded on the platforms with sufficient lateral support. It should in this connection be pointed out that, at the entry of circuit part A as also at the exit of circuit part E, the transporting apparatus according to the invention further provides a comb 6 for facilitating the loading and unloading, respectively, of the loads. Only a very small part of this comb is shown in FIG. 4, where one of its teeth is seen to project between two ribs of a plate 5. Further details of the conveyor grooves are disclosed in copending application Ser. No. 143,989 filed Mar. 17, 1971.

On its underneath surface, each platform is provided with two annular supports 7 (FIG. 4) which are located, one, near the longitudinal edge b of the platform

(see FIG. 2) and the other, near the second longitudinal edge of the latter, the distance between the axes of these two supports, projected on to one or other of the parallel edges of the corresponding platform, being equal to the distance between the axes of symmetry of the rails 3 and 4 along, for instance, part A of the circuit.

In each of the supports 7 with which are provided the various platforms is mounted a turret 8 bodily associated with the upper part of a trolley 9 provided with two grooved rollers g_1 and g_2 by means of which each trolley 9 rolls over the outer face of the corresponding rails 3 or 4. On the rotational axis of each of these rollers, a_1 and a_2 respectively, there is pivotally mounted a lever l_1 and l_2 respectively, carrying at its free end a second roller, g_3 and g_4 respectively, rotatably mounted on the corresponding lever and moving in contact with the inner face of rail 3 or 4. It will moreover be observed that the free end of the levers l_1 or l_2 carries two buffers u_1 and u_2 , and u^*_1 and u^*_2 , respectively, the terminal portion of which extends to a distance from the pivotal axis of rollers g_3 and g_4 , respectively, which is greater than that of the radius of these rollers thereby to avoid contact between the rollers belonging to the trolleys of one of the platforms and the rollers g_4 of the trolleys on the preceding platform, in particular when these platforms are travelling over the two secondary segments $3c$ and $4c$, and $3d$ and $4d$, respectively, of the loops formed by the rails 3 and 4. Further, each trolley is provided at each of its ends with a buffer x_1 or x_2 respectively by means of which the trolleys of each platform come into contact with the corresponding trolleys of the adjacent platforms, in particular when all

of these platforms are moving over the secondary segments 3c, 4c, 3d and 4d mentioned earlier.

Each platform of the transporting apparatus is capable of being hooked to an adjacent platform by means of two hooking mechanisms (which are further described in U.S. Pat. No. 3,695,183 of Oct. 3, 1972 each comprising a male portion and a female portion, the components of one of these mechanisms being visible in FIGS. 5 and 6).

When the platforms are moving for instance over the segments 3c and 4c of the guide rails 3 and 4 over part A of the circuit, the longitudinal axes of the two parts of these mechanisms extend, one, in the sectional plane IV—IV (FIG. 2), as shown in FIG. 4 and, the other, in a plane parallel to the first. As can be seen in the drawing, these two planes pass respectively through the pivotal axes of the first and second trolleys 9 carried by each platform.

The various platforms are each formed on their longest side faces with two longitudinal grooves p_1 and p_2 the cross-section of which is cylindrically shaped with a common diameter. It is these grooves that are anchored the first and second portions, respectively, of each of the hooking mechanisms.

The description which will now follow only relates to one of these mechanisms but it also applies to the other. It should be read with the assistance of FIGS. 4 and 6.

In the groove p_1 of each platform is mounted a socket member 10 which is provided on its outer surface with a liner of anti-friction material 11 and which is formed with a transverse passage 10a into which is inserted, and secured by a pin 12, the end 13a of a tie-rod 13. By virtue of the liner 11, the socket member 10 may not only be pivoted in the housing p_1 but can also be made to slide axially therein; it is of course also possible to keep the socket member stationary and to move the platform angularly or axially in relation to this socket member.

The tie-rod 13 has a portion 13b, of rectangular cross-section, adjacent a shoulder 13c, and, at its free end, an abutment 13d. Between these two elements, i.e. the shoulder and the abutment, the tie-rod is of cylindrical outline.

In the groove p_2 of each platform are secured two substantially cylindrical components 14A and 14B which are disposed in substantially co-axial relationship and which define between themselves a space 15.

It is to be noted that the arrangement of the components 14A and 14B inside the groove p_2 is such that the longitudinal axis of symmetry of the space 15 lies substantially parallel to the longitudinal axis of the trolley 9 (FIG. 4), when the latter is oriented at right angles to the longitudinal sides of the corresponding platform.

In component 14B is bored a cylindrical passage 16 (FIG. 6) opening in the space 15. The component 14A is formed with a cylindrical recess 17 (FIG. 6) opening in the space 15, which extends co-axially with the passage 16 and which has the same diameter as this passage. This passage and this recess are intended to receive first and second pivot members 18 and 29, respectively, which are secured in diametrically opposite positions to the side face of a socket member 20.

In the component 14A there is also cut a slot 14* (FIG. 5) in which is slidably mounted a rectangular "welded-on" extension of a locking bolt 22, such that

the bolt 22 may slide guided by the extension in the slot.

To one end of the bolt 22 is welded a stop member 24 which engages a similar step 25 in axial alignment with the first step to prevent excessive movement. A spring 26 is mounted over and abutting the two steps to bias the bolt 22 to one side of its movement and thus take up a locking position (indicated in FIG. 5), the unlocking action taking place by exerting a thrust, from left to right in the drawing, on a roller 27 pivotally mounted at the end of a lug 22b on the locking bolt 22.

To ensure that the locking bolt will be held on the component 14A, the locking bolt is provided with a longitudinal slot 22d (FIGS. 5 and 6) between the edges of which extends a projecting element 28 solid with the component 14A which has provided a rectangular head 28a larger than the slot 22d.

As will be observed from FIG. 5, the locking bolt is formed at its left end with a notch of substantially rectangular shape 22e. This notch is defined by two teeth 22f and 22g and its width is slightly greater than that of the rectangular portion 13b of rod 13. Thus, as soon as two platforms, e.g. platforms 2a and 2b, are sufficiently near each other, or in contacting relationship, as is the case with two platforms in FIG. 4, and if nothing restrains the action of the spring 26, the rod 13 of one of the platforms, here that of platform 2a, is fully inserted inside the platform 2b, by sliding the socket member 20 mentioned earlier; further, if nothing restrains the action of the spring 26, the locking bolt 22 that is fixed on the platform 2b engages round the rectangular portion 13b of the rod 13 that is carried by the other platform, 2a. It follows therefore that if platform 2b is driven from left to right in the drawing (FIG. 4), this platform also draws with it platform 2a, the abutment 13c on the rod 13 coming to bear on the locking bolt 22 of platform 2a.

When the locking bolt is moved out of its locking position platform 2b releases itself from platform 2a, and, if only the first is driven, it moves away from this platform at most by a length limited by contact of the abutment 13d of rod 13 (FIGS. 4 and 6) with one end of the socket member 20.

As will be observed, the platforms of the transporting apparatus according to the invention are able to occupy two separate relative positions, one in which the platforms are close together and the other in which the platforms are remote from each other.

When the platforms travel over the upper main segment of the circuit loop, which is observed for the conveyance of loads, they are in close relationship so as to form a continuous band. This is also the case when these self-same platforms move over the lower main segment of the circuit.

The platforms are however in spaced-apart relationship when they are travelling over the two secondary segments of the circuit (parts 3c and 4c, 3d and 4d of rails 3 and 4). FIG. 4 shows the relative position of the platforms over these circuits segments.

For the platforms to be able to occupy the position shown in FIG. 4, it is essential that the locking bolts 22, for hooking the platforms together two by two, be opened. To this end, the illustrated transporting apparatus comprises a first pair of ramps for actuating the locking bolts 22 of the two hooking mechanisms connecting each platform to a neighbouring platform, these ramps extending along the segments 3c and 4c of

the loops formed by the guide rails 3 and 4 and serving to push back the roller 27, associated with each locking bolt, from the position corresponding to the locked position of the mechanism to the unlocked position. These ramps are not shown.

The transporting apparatus is also provided with another pair of similar ramps, also not shown in the drawing and extending along the segments 3d and 4d of rails 3 and 4.

As described, each platform is connected to a neighbouring platform by two hooking mechanisms having a male part and a female part. The illustrated mechanism, which is that connecting the platforms 2a and 2b along the section of FIG. 4 has its female part anchored in the groove p_2 of platform 2a and its male part anchored in the groove p_1 of platform 2b.

It should at this point be pointed out that the second hooking mechanism, whose longitudinal axis lies in a parallel plane has unlike the first, its male part anchored in the groove p_1 of platform 2a and its female part anchored in the groove p_2 of platform 2b. However, whereas the anchoring of the female part of each mechanism in the corresponding groove is such that it can, under no circumstances, move axially in this groove, such is not the case as regards the male part of the mechanism, since the latter is slidably mounted in the corresponding groove. It is this structural feature of the hooking mechanisms which enables the platforms to move longitudinally in relation to each other when moving over an acceleration or deceleration section of the circuit, and yet remain hooked in pairs.

As may be seen in FIG. 2 the platforms 2a, 2b, ..., 2n pass through the central high speed zone with their short sides substantially in alignment so that the straight edge formed may be brought into close proximity with the edge of the belt 1 for load transference. In this zone the platforms are moving rapidly and are only braked and driven at spaced-apart intervals by the wheels r_5 , r_6 , r_1 and r_2 . Thus it is necessary to provide locking means between the platforms to prevent relative lateral sliding of the platforms such sliding is particularly likely to occur in the event of jamming of the system or emergency braking.

FIG. 13 shows the arrangement of the adjacent platforms 2f, 2g and a stop member 51 is provided against which the sliding socket member 10 may abut. The detailed arrangement and locking device is shown in FIGS. 14, 15 and 16.

Attached to the stop member 51 is an angled latch 52 which is reciprocable in a vertical direction normal to the platform surface. The latch is in the form of an angled member having two arms 53 and 54 approximately at right angles. Arm 54 extends in the direction of the axis of the groove p_1 parallel to and spaced a small distance from the forked locking bolt 22. Formed in the upper surface of the arm 54 is a groove 55, the groove 55 engaging the previously described rectangular head 28a of the locking bolt retainer. The arm 53 has a rectangular slot 56, providing for the mounting of the latch on the stop member 51, the slot accommodating a guide 57 attached to the stop member 51 by a screw 58, the screw also retaining a disc 59 which overlaps the sides of the slot 56 and holds the latch 52 on the guide 57. Arm 53 also has a hollow extension 60 containing a compression spring 61. Spring 61 acts on the guide 57. Thus the spring 61 tends to maintain the latch in an upward or locking position. The outer end of the arm

54 is chamfered at 62 and as the platforms slide laterally and enter the high speed section, the socket member 10 and stop member 51 approach each other. At the end of the lateral movement the socket member 5 and stop member come together. As this occurs, the head 28a engages the chamfered portion 62 of the arm 54, forcing the latch 52 downwards. Socket member and stop member finally come into contact and the latch member moves upwards, the head 28a engaging 10 in the groove 55, thus locking the two members together. The latch 52 is unlocked at the end of the high speed zone by a cam surface on a support structure engaging the end of the extension 60 of the arm 53, moving the latch downwards against the action of the 15 spring. This releases the head 28a and allows the relative sliding of the platforms with the associated parting of the socket member 10 and stop member 51.

In the high speed return zone (shown in FIG. 3) the 20 platforms are at the other extreme of their sliding contact and again to withstand sudden deceleration which can cause inadvertent platform sliding, it is desirable to lock the platforms by locking the sliding mechanisms. The platform correlation is shown in FIG. 17 and FIGS. 18, 19 and 20 show the detailed arrangement and 25 locking mechanisms.

As seen in FIG. 17 the sliding socket members 10 of 30 adjacent platforms move towards each other and a stop is reached when each socket member 10 abuts the cylindrical member 14b which is mounted in its groove (p_1 or p_2). A latch mechanism for locking the members in this abutting relationship comprises a latch member similar to the above latch and as described below attached to the member and engaging a stud on the other member.

35 On one member 14b₁ is mounted an angled latch 65, this latch, in the present example, being of substantially the same form as the latch 52 in FIGS. 14, 15 and 16. The latch has arms 66, 67 substantially at right-angles, and is mounted in the reverse position to that of latch 52, that is arm 66 is uppermost and arm 67 extends downwardly in a direction away from the top surface of the platform. Arm 66 has a groove 68 which engages with a stud 69 mounted on the member 14b₂ of the adjacent platform. The latch is mounted on the member 14b₁, on a guide 70 which is secured to a slot 71 in arm 40 67, by means of a screw 72 and a disc 73. Arm 67 has a hollow extension 74 containing a compression spring 75 acting on the guide 70. The end of the arm 66 is chamfered at 67.

45 The action of locking is similar to that when locking the platforms in the load-carrying zone. As the socket members 10 approach each other, the stud 69 engages the chamfered end 67 of the arm 66, forcing the latch 65 upwards until eventually the stud is received into the groove 68. The members are then locked together until a cam surface, mounted on the conveyor support structure engages the end of the extension 74 of arm 67, moving the latch downwards as shown in the FIGS. 18 and 20 releasing the stud 69 when the socket members, and thus, the platforms can move sideways relative to each other.

50 The drive system operation will now be described with reference to FIGS. 1-3. The circuit comprises two other portions along which an acceleration and a deceleration of the platforms takes place; they are portions D' (acceleration) and B' (deceleration) along which 55 this acceleration or deceleration, as the case may be,

can take place under practically any conditions since these circuit portions are not meant to convey any loads, whether people or goods, but are included in the circuit portion along which the platforms are recycled.

The various platforms $2a, 2b, 2c, \dots, m, \dots, n$, etc. are principally made up of a shaped structural member made of aluminium. This makes it possible for the platforms to be driven relatively easily, in particular over those circuit portions, such as the platform acceleration or deceleration portion, over which such a drive is generally very complicated to achieve as can be seen for instance by examining the solution proposed by the already mentioned U.K. Patent No. 1,034,969 or by the more recently issued British Pat. No. 1,127,433. In the illustrated transporting apparatus, the platforms are accelerated and braked by linear induction motors of which the armatures are successively constituted by the various platforms of the apparatus and of which the stators, referenced S_1 and S_{11} in the acceleration section and S_{12} to S_{17} in the deceleration section, are arranged in a row beneath the plane of motion of the platforms and in positions which are tangential as regards their longitudinal axes to the path followed by the centres of gravity of the platforms during acceleration and deceleration, respectively.

At each end of the two main segments of the loop the drive is provided by pairs of screws V_1 and V_2 , and V_3 and V_4 , respectively, at the left-hand end of the loop, and V_5 and V_6 , and V_7 and V_8 , respectively, at the left-hand thereof, the platforms moving over portion D of the circuit and over the portions of the lower main segment of the circuit, lying between the pairs of screws V_3 and V_4 , on the one hand, and V_7 and V_8 , on the other hand, are driven by four tyred wheels r_1 and r_4 . The first two wheels r_1 and r_2 , act on the moving platforms along the upper main segment of the circuit whereas the other two serve to drive the platforms moving along the lower main segment.

The wheels r_1 and r_2 are kinematically solid with each other. They are powered by a common d.c. motor M_1 (FIG. 1). FIGS 7 and 8 of the accompanying drawing show in a particularly detailed manner how they and their actuating mechanism are mounted. In particular, it will be observed that each of these wheels is actuated through an angular drive transmission Ra_1 , in the case of wheel r_1 , and Ra_2 in the case of wheel r_2 , these two angular drive transmissions being connected to each other by a shaft A_1 and drive transmission Ra_1 being connected to a speed-reducing means Rv powered by the previously mentioned motor M_1 . To the rim of each of the wheels r_1 and r_2 is secured a brake disc d_1 or d_2 , respectively, on which can act hydraulically operated jaws m_1 and m_2 , respectively. Each assembly consisting of a pair of jaws, m_1 or m_2 , and by a disc, d_1 or d_2 , respectively, constitutes a disc brake which is in all respects identical to those in the motor vehicle industry.

The wheels r_3 and r_4 are driven by d.c. motors, M_2 and M_3 , through speed-reducing means Rv_2 and Rv_3 . On the wheels r_3 and r_4 are also mounted disc brakes similar to those fitted on the wheels r_1 and r_2 .

It should at this juncture be pointed out that the platforms of the transporting apparatus can further be braked through the intermediary of two other wheels r_5 and r_6 , which have no driving action but which are also fitted with disc brakes. The operation of the disc brakes associated with all of the wheels r_1 to r_6 is synchronised. The same applies to the motors M_1 to M_3 which are,

moreover, speed controlled, for instance by acting on their energization, from a control station, not shown, which in particular includes a regulator adapted to maintain the speed of the platforms travelling over circuit portion C at the previously mentioned value V , this being the speed of band 1 and to return the speed of the platforms to this value when it has strayed therefrom, for instance as a result of a relatively large change in the load being conveyed. This regulator is so chosen as to have a torque/speed characteristic as flat as possible for a relatively large change in speed in the region of the mentioned value V so that any increase or decrease in the load being conveyed by the apparatus will only cause a slight change in the speed of the platforms.

As described in U.K. Patent Application 43051/70 mentioned earlier, such speed control makes it possible to impose on the linear motors S_1 to S_{11} , S_{12} to S_{17} , the slip with which they are required to operate, i.e. the speed at which the various platforms travel past the various points of the acceleration or deceleration section of the circuit that are subjected to these motors.

As described earlier, the drive for the platforms over the terminal parts of the main segments of the loop formed by the rails 3 and 4 is provided by means of pairs of screws V_1 , V_2 and V_3 ; V_4 and V_5 ; V_6 and V_7 , V_8 . In FIGS. 9 to 12 it will in particular be observed that the pairs of screws V_5 , V_6 and V_7 , V_8 are independently actuated by two separate motors M_4 and M_5 whereas the pairs of screws V_1 , V_2 and V_3 , V_4 are both driven by one and the same motor M_6 . The reason for this difference in the drive system will be given further on.

The screws V_1 to V_8 have an identical pitch and the width of their tread is slightly greater than the diameter of rollers g_5 and g_6 (FIGS. 9-11) that are rotatably mounted beneath each one of the platforms of the apparatus near the oblique sides thereof, with a spacing corresponding to that of the screws of each pair.

Each screw is intended, when rotated, axially to drive these rollers and hence the platform to which they are secured. To this end, the screws V_5 and V_6 and the screws V_7 and V_8 are mounted on a corresponding shaft, only that for screw V_5 , A_2 , and that for screw V_7 , A_3 , being visible in FIG. 10 of the drawing.

On the shaft of each screw V_5 to V_8 is keyed a pulley Pv_5 to Pv_8 over which passes a belt, C_5 to C_8 , actuated by a second pulley Pv_9 to Pv_{12} . The pulleys Pv_9 , Pv_{10} , Pv_{11} , Pv_{12} , are respectively keyed on the output shaft of the angular drive transmissions Ra_3 , Ra_4 , Ra_5 , Ra_6 . The angular drive transmissions Ra_3 and Ra_4 are kinematically connected by a shaft A_4 whereas the angular drive transmissions Ra_5 and Ra_6 are connected to each other by a shaft A_5 . The angular drive transmissions Ra_4 and Ra_6 are moreover respectively connected to the motors M_4 and M_5 via speed-reducing means Rv_4 and Rv_5 .

Like the motors M_1 , M_2 and M_3 , the motors M_4 and M_5 are d.c. motors and their speed is also controlled by acting on their energization with the regulator mentioned earlier. It is essential that the screws V_5 to V_8 , which are dependent on these motors, should drive the platforms coming within their reach at a speed that is identical to that at which these self-same platforms are driven by the motors M_1 , M_2 and M_3 . It should however be pointed out that although the motors M_4 and M_5 rotate at the same speed it is not possible to replace them by a single motor as will be explained later, if it is desired to compensate the heat deformations that can affect both the platforms and the rails 3 and 4.

Such however is not the case as regards the drive for the screws V1 to V4, which are powered by the same motor M6.

Each screw is mounted on a separate drive shaft, only the shaft of screw V2, A6 and the shaft of screw V4, A7, being visible in FIG. 12 of the drawing. On its respective shaft each screw carries a pulley Pv13 to Pv16, for screws V1 to V4 respectively, which pulleys have wound thereon a belt C9 to C12, respectively, actuated by a second pulley Pv17 to Pv20 respectively. The pulleys Pv18 and Pv19 are keyed on the output shaft of the angular drive transmission Ra7, whereas the pulleys Pv17 and Pv20 are mounted on the output shaft of another angular drive transmission, Ra8, connected to the angular drive transmissions Ra7 by an intermediate shaft A6. The angular drive transmission Ra8 is connected to the motor M6 through a speed-reducing means Rv6.

As in the case of the motors M4 and M5, the motor M6 is also a d.c. motor and its speed of rotation can be varied by acting on its energization. This motor is also controlled by the above-mentioned regulator so as to operate in perfect synchronism with the motors M1 to M5.

As has been indicated, the length of each of the rails 3 and 4 is so chosen that, at ambient temperature, e.g. of the order of 15°C, it exceeds the total length of the train of platforms by a few mm, or even a few cm. By taking this precaution, the described transporting apparatus can withstand without difficulty temperature differences above or below the indicated ambient level, as this difference in length leads to the formation of a gap EL between two adjacent platforms along the circuit portion formed by segments 3b and 4d, whereas everywhere else the platforms are in mutual contacting relationship via their buffers x₁ and x₂. It should in this connection be pointed out that, as soon as the platform after having travelled over portion E of the circuit, is released by the screws V5 and V6, the speed of this platform increases under the action of earth attraction and "drops" on to the preceding platform whilst moving away, at its buffers, from the following platform, this platform still being in engagement with the screws V5 and V6. The distance between these two platforms corresponds to the play EL mentioned earlier; which play can be more or less sizeable depending on the thermal deformations to which the apparatus is subjected. The extent of this play can besides be adjusted by varying the angular setting of the screw V7 in relation to that of the screw V5, it being possible to perform this operation since these screws are driven in wholly independent manner in relation to each other.

At the left-hand end of the circuit of the transporting apparatus, no play can however be allowed to occur since the screws V1 and V3, and V2 and V4, respectively, are driven in synchronism and since the action of gravity on the platforms travelling over the portions 3c and 4c of rails 3 and 4 precisely tends to maintain these platforms in permanent abutting relationship with each other via their buffers x₁ and x₂ (FIG. 4).

By virtue of the various drive means that have been described, the platforms of the apparatus which travel over the upper main segment of the circuit, this segment being in fact the only one to be used for the conveyance of loads, whether goods or people, takes place without discontinuity and at a speed which only varies

very little for even quite sizeable variations in the load being conveyed.

It is to be noted that the platform in the parts outside the acceleration and deceleration section of the circuit can also be driven, according to a variant, by asynchronous motors having a sufficiently flat torque/speed characteristic to provide the apparatus with good speed stability. It is known that the main feature of such motors resides in the fact that they are self-regulating and 10 that it suffices to supply them with current having a well-set frequency to cause them to rotate at a given speed exclusively dependent on the number of poles in the motor.

The invention is of course not limited to what is described or illustrated: in particular, it will be appreciated that the above set forth inventive concepts can be applied to transporting apparatus in which the travel circuit for the platform could be different from that illustrated in FIGS. 1 and 3 of the accompanying drawings and correspond to either of the circuits illustrated by some of the figures in U.K. Patent No. 1,034,969 mentioned earlier.

One alternative arrangement to FIG. 1 is to pass the deceleration part of the conveyor, i.e. the additional speed change zone, under the high speed conveyor 1 as shown in FIG. 21. In this arrangement it is not necessary to curve the high speed belt as in FIG. 2, but the conveyor only acts as an accelerator and a barrier 80 is provided to ensure the load is transferred to the high-speed belt.

The device may be run in the opposite direction to provide a decelerator or unloading station for the high speed belt. The return run of the high-speed belt may be under the platforms conveyor as well as under the load-carrying portion of the high-speed dependent on the installation.

Another arrangement is shown in FIG. 22 in which the acceleration and deceleration sections of the conveyor are utilised with a straight high-speed belt 1. The acceleration zone 81 of the platform conveyor curves until it runs parallel with one side of the belt 1 and a barrier 82 running at an acute angle to the direction of travel ensures the load is transferred to the belt. The conveyor platforms are then unlocked and the guide rails curve such that the platforms travel around the curve in the region 83 until they are brought back into line and locking engagement alongside the other side of the belt. The deceleration portion 84 of the conveyor is then usable for decelerating loads taken off the belt 1. A barrier 85, at an acute angle across the conveyor platforms prevents load transfer prior to the locking together of the platforms.

In yet another arrangement not illustrated the barriers 82, 85 of FIG. 22 may be dispensed with and by allowing headroom between the platforms and the under surface of the belt 1 a load overshoot may be allowed whereby a load may remain on the platform conveyor and be decelerated once again. In this case the useful area of the platforms is somewhat restricted in width due to the small clearance between the platforms as they are unlocked for the curves.

Still another arrangement uses only the first acceleration portion of the S-shaped platform conveyor as a loading station. The platforms may be returned after a high-speed turnover via a similar curved path to re-enter the accelerator. At another point in the path of the high speed belt a deceleration unit may be provided

again comprising only half of the full S-shaped conveyor described above such an arrangement therefore provides loading or unloading points where required along the length of the high-speed belt.

What I claim is:

1. Transporting apparatus comprising a series of transport platforms intended to travel over a closed circuit having a low-speed zone, a high-speed zone and an intermediate speed-change zone between the low and high-speed zones, the speed change zone being in the form of a curve and the cosine of the angle between tangents at the two ends of the curve corresponding to the ratio of the platform speeds in the low-speed and high-speed zones, and a platform-return run curved at least in part as the speed-change zone, wherein the circuit comprises a stretched out loop comprising, firstly, two main segments which are contained one in a first horizontal plane and the other in a second, subjacent, horizontal plane, and secondly two secondary segments which connect the ends of said main segments to form the closed circuit, segment segment in the upper main segment of the loop comprising at least the said low, high and speed-change zones of the apparatus and the segment in the lower main segment of the loop comprising at least the curved part of the platform-return run, the platforms being driven over the closed loop by means comprising: in the speed-change zones a succession of linear motors whose stators are disposed to one side at least of the plane of motion of the platforms, along the path followed by the centers of gravity of these platforms, and whose armatures are formed by at least one metallic mass associated with each platform, in the terminal portions of each main segment of the loop a pair of rotary screws extending on opposite sides of the path followed by the centers of gravity of the platforms, in a plane parallel to the plane of motion of the platforms and over a set length from the end of this main segment, the thread of each screw receiving a projection element on each platform when the platform reaches the entry end of the screw, and axially pushing the projecting element and the platform towards the exit end of the screw, a driving device being provided for the screws; and over the other portions of the said main segments of the loop, a driving mechanism engaging with the platforms in at least a portion of each end of the segments.

2. Transporting apparatus according to claim 1 wherein the upper main segment of the loop comprises an additional low-speed zone and an additional speed-change zone between the high-speed zone and the additional low-speed zone, the said additional speed change zone being in the form of a curve and the cosine of the angle between tangents at the ends of the curve corresponding to the ratio of the platform speeds in the high-speed and additional low-speed zone, and the lower main segment of the loop comprising the return run of the conveyor comprises low-speed end zones one at each end of the segment, a high-speed central zone and two curved speed change zones, one between each end zone and the high-speed zone, each being curved as the speed change zones in the upper main segment.

3. A conveyor system comprising a transporting apparatus according to claim 2 and an endless belt moving at a constant speed substantially equal to the platform speed in the high-speed zone of the loop wherein the speed-change zone accelerates a load from the low speed to the high speed for transfer from the high speed

zone to the endless belt, the path of the high speed belt being curved so as to avoid the additional speed-change zone and the additional low speed zone which decelerates a load transferring from the high speed belt to the high speed zone.

4. A conveyor system according to claim 3 wherein a barrier is provided to move loads from the high-speed zone of the zone of the transport apparatus onto the endless belt.

10 5. A conveyor system comprising a transporting apparatus according to claim 2 and an endless belt moving at a constant speed substantially equal to the platform speed in the high speed zone of the loop wherein the speed-change zone accelerates a load from the low speed to the high speed for transfer to the endless belt and the additional speed change zone and additional low speed zone are accommodated between the load-carrying and return runs of the endless belt.

20 6. A conveyor system according to claim 5 wherein a barrier is provided to move loads from the high-speed zone of the transport apparatus onto the endless belt.

25 7. A conveyor system comprising a transporting apparatus according to claim 2 and an endless belt moving at a constant speed substantially equal to the platform speed in the high-speed zone of the loop wherein the high-speed zone runs adjacent to one side of the belt for transfer of loads onto the belt and then passes under the belt and runs adjacent to the other side of the belt for transfer of loads from the belt for subsequent deceleration in the additional speed change zone.

30 8. Transporting apparatus according to claim 1 wherein each platform is provided with means enabling detachable, edge to edge, hooking engagement with the adjacent platforms, and control means are provided for controlling said hooking means, adapted to engage said hooking means for as long as the platforms move along the main segment of the circuit loop and to release the platforms from hooking engagement when travelling over the said secondary segments of said loop.

35 9. Transport apparatus according to claim 8 wherein the driving mechanism comprises at least one wheel mounted on an axle having driving means for engaging the underside of each of the platforms in turn.

40 10. Transport apparatus according to claim 9 including an unpowered wheel for engaging the underside of each platform and braking means for the unpowered wheel.

45 11. Transport apparatus according to claim 9 wherein the wheels have rubber pneumatic tires.

12. Transport apparatus according to claim 8 comprising at least one wheel mounted on an axle having braking means, the wheel engaging the underside of each of the platforms in turn.

55 13. Transport apparatus according to claim 1 wherein synchronising means are provided for the various pairs of screws and the driving mechanism.

60 14. Transport apparatus according to claim 1 wherein at ambient temperature, the length of the circuit is greater than the length that is effectively occupied by all of the platforms.

65 15. Transport apparatus according to claim 14 wherein the pair of screws at the entry of the upper main segment of the loop and the pair of screws disposed at the exit of the lower main segment are kinematically solid with each other, and the pair of screws at the exit of said upper main segment and the pair of

17

screws disposed at the entry of the said lower main segment are kinematically independent of each other.

16. Transport apparatus according to claim 1 wherein the linear motors are induction motors.

17. A conveyor system according to claim 16

18

wherein a barrier is provided to move loads from the high-speed zone of the transport apparatus onto the endless belt.
